UNITED STATES PATENT OFFICE

152,418

DESIGN FOR A BICYCLE BELL

Wyman N. Hill, East Hampton, Conn., assignor
to The N. N. Hill Brass Company, East Ham-
pton, Conn., a corporation of Connecticut

Application November 7, 1947, Serial No. 142,378

Term of patent 14 years

(Cl. D72—1)

To all whom it may concern:

Be it known that I, Wyman N. Hill, a citizen
of the United States, residing at East Hampton,
in the county of Middlesex and State of Con-
necticut, have invented a new, original, and orna-
mental Design for a Bicycle Bell, of which the
following is a specification, reference being had
to the accompanying drawing, forming part
thereof.

The characteristic feature of my design con-
sists in having one of its members of substantially
conical form.

Fig. 1 is a perspective view of a bicycle bell
showing my new design;

Fig. 2 is a side view of Fig. 1; and

Fig. 3 is an end view thereof.

I claim:

The ornamental design for a bicycle bell, sub-
stantially as shown and described.

WYMAN N. HILL.
